[57] ABSTRACT

A photographic film unit of the self-processing type

includes preregistered, superposed, photosensitive and process elements mounted on a underlying carrier sheet having a cooperating pod for supplying a fluid processing composition to the two elements and a trap for receiving and retaining any excess processing composition from the elements. The elements are easily separable from the carrier sheet, pod, and trap, the pod and trap remaining with the carrier sheet for convenient disposal after processing. The trap is formed by an extension of the carrier sheet that is folded around and separably coupled to the trailing end of the upper element. Moisture-sensitive cement is provided on an interior surface of the trailing ends of the two elements to couple those ends to each other upon application of compressive force urging the two ends together after the excess processing composition has passed between them, a spacing member being mounted on the carrier sheet beneath and parallel with those ends to assist the compressive force in urging them together. Moisture-sensitive cement is also provided on an interior surface of the trap to seal the trap closed upon application of compressive force after the excess processing composition has passed into it, a spacing member being mounted on the carrier sheet extension to assist the compressive force in closing the trap.

PHOTOGRAPHIC FILM UNIT

CROSS-REFERENCE TO RELATED APPLICATIONS

Reference is made to commonly assigned, copending U.S. Pat. applications Ser. No. 033,677, entitled PHOTOGRAPHIC APPARATUS and filed May 1, 1970 in the name of Donald M. Harvey; Ser. No. 70,835, entitled PHOTOGRAPHIC FILM UNIT and filed Sept. 9, 1970 in the name of Hubert Nerwin now abandoned; Ser. No. 70,836, entitled FILM UNIT and filed Sept. 9, 1970 in the name of Hubert Nerwin; and Ser. No. 111,465, entitled PHOTOGRAPHIC FILM UNIT and filed concurrently with this application in the name of Hubert Nerwin.

BACKGROUND OF THE INVENTION

1. Field of the Invention

This invention relates generally to photographic film units of the self-processing type, and particularly to such film units comprising preregistered photosensitive and process elements removably mounted on a carrier sheet.

2. Description of the Prior Art

It is well known in the photographic arts to provide film units with materials for processing the units immediately after their exposure. Generally such units include a photosensitive element, comprising a support having thereon at least one layer of photosensitive material, and a second element adapted to be registered over the photosensitive element for processing. A viscous fluid processing composition is released from a rupturable pod at one end of the unit and is spread toward the other end by passing the unit between juxtaposed pressure-applying members that distribute the composition in a layer of predetermined thickness between the two elements. The distributed composition then permeates the layers of the unit to effect development of the photosensitive layer(s), and an imagewise distribution of dye or silver diffuses to or is formed on an image-receiving layer in either the photosensitive or second element to form the finished print.

In most presently commercial film units, generally referred to as being of the "peel-apart" type, the photosensitive and second elements are separated before and during exposure, and thereafter are brought into superposition for processing. The image-receiving layer is in the second element, and that element is stripped from the rest of the unit after processing to provide a positive, right-reading print. Such units are disclosed, for example, in U.S. Pat. No. 2,698,243, No. 3,080,805, and No. 3,511,659.

This invention is concerned with a more recently developed type of film unit, generally referred to as a "preregistered" or "integral" unit, in which a photosensitive element and a process sheet or second element are supplied as a permanently registered, integral pair of elements. The elements of such a unit are superposed prior to exposure and remain superposed after processing. The process sheet or second element is transparent to permit exposure of the photosensitive material from the "top side" of the unit, and the image-receiving layer is located in either the process sheet or, preferably, the photosensitive element to provide a positive image that does not need to be stripped from the rest of the unit. Film units of the type having the image-receiving layer located in the process sheet are dis-

closed, for example, in French Patents No. 2,006,255 and No. 2,006,256, granted to Polaroid Corporation and published Dec. 26, 1969. Film units of the type having the image-receiving layer located in the photosensitive element are disclosed, for example, in commonly assigned, copending U.S. Pat. application Ser. No. 027,990, entitled PHOTOGRAPHIC FILM UNIT FOR DIFFUSION TRANSFER PROCESSING, filed Apr. 13, 1970 in the name of Harold E. Cole now abandoned.

The development of commercially practical film units of the preregistered or integral type has constituted a significant step toward alleviating some of the problems inherent in peel-apart units, such as those encountered in first superposing and then separating the photosensitive and image-receiving elements. At the same time, however, numerous and often unexpected new problems have been encountered. For example, with a peel-apart unit it is relatively easy to separate the finished print from its leader, pod, trap, and other processing waste material. Such separation is facilitated by the moistened condition of the interface between the photosensitive and image-receiving elements, the moistened condition resulting from the distribution of the processing composition between those elements. In integral units, however, the finished print comprises the photosensitive element and process sheet permanently attached to each other, and separation of the processing waste materials therefrom may be more difficult because it does not occur at the moistened interface provided by the distributed processing composition.

In commonly assigned, copending U.S. Pat. applications Ser. No. 033,677, entitled PHOTOGRAPHIC APPARATUS and filed May 1, 1970 in the name of Donald M. Harvey, and Ser. No. 70,835, entitled PHOTOGRAPHIC FILM UNIT and filed Sept. 9, 1970 in the name of Hubert Nerwin now abandoned, there have been disclosed integral film units with associated leaders, pods, and traps that provide solutions to certain of the aforementioned problems. A particular problem not completely solved in those two applications is that of providing an efficient means of conveniently and positively sealing the trailing ends of the photosensitive element and process sheet together after any excess processing composition has passed between those two ends to the trap adjacent thereto. A similar problem not there solved is that of providing an efficient means of conveniently and positively sealing the leading end of the trap closed after the fluid has passed into it. In the aforementioned U.S. Pat. No. 2,698,243, disclosing a film unit of the peel-apart type, a trap is formed by bringing together opposing portions of the carrier sheets bearing the photosensitive and second elements, the trap being sealed closed, after the excess processing composition has passed into it, by means of a strip of moisture-sensitive or pressure-sensitive adhesive material applied to one of the carrier sheets. In the aforementioned French Patents No. 2,006,255 and No. 2,006,256, disclosing a film unit of the integral type having the image-receiving layer located in the process sheet, the trap, which is incorporated into and remains a part of the trailing end of the film unit, is sealed closed, after the excess processing composition has passed into it, by means of the moisture-and pressure-sensitive adhesive property of the surfaces being sealed. Nowhere in the prior art known to Applicant is there disclosed a convenient, positive, fool-proof

means of sealing closed the trailing ends of the photosensitive element and process sheet of an integral type of film unit, and the leading end of the trap used with such a unit, where the trap is to be detached from the photosensitive element and process sheet comprising the finished print after any excess processing composition has been received by the trap. Consequently, for such a film unit an efficient means of conveniently and positively sealing the trailing ends of the photosensitive and process elements together after excess processing composition has passed therebetween, and an efficient means of sealing the leading end of the trap closed after the excess processing composition has passed into the trap, are highly desirable in order to prevent unintended escape of any residual processing composition from between the two elements and the trap, respectively, subsequent to separation of the elements from the trap, particularly in view of the possible effects which the caustic nature of such composition may have on the surrounding environment, such as the skin or clothing of the user.

SUMMARY OF THE INVENTION

Accordingly, an object of the present invention is to provide an improved self-processing film unit of the integral type, comprising preregistered photosensitive and process elements and a separable trap, wherein the unit includes an efficient means of conveniently and positively sealing the trailing ends of the two elements closed after any excess processing composition has passed between those ends to the trap. Another object of the invention is to provide such an improved film unit wherein the unit further includes an efficient means of conveniently and positively sealing the leading end of the trap closed after the excess processing composition has passed into the trap. A further object of the invention is to provide such an improved film unit wherein the film unit further includes means for facilitating the separation of the trap from the two elements. A still further object of the invention is to provide such an improved film unit at a minimum cost of manufacture in order to provide the benefits obtainable from such a unit at a minimum cost to the ultimate user.

To meet these and other objects, the present invention provides an improved self-processing film unit comprising a pair of preregistered, superposed lower and upper elements including a layer of photosensitive material for establishing a developable latent image of a subject to which the photosensitive material can be exposed and a layer of image-recording material for recording a visible image in response to development of the latent image, each of the two elements having first and second longitudinal marginal portions along which the elements are permanently coupled to each other, first and second transverse marginal portions interconnecting the longitudinal marginal portions, and an image portion intermediate the marginal portions, each portion of each element having an inward-facing surface, each inward-facing surface of one element facing a corresponding inward-facing surface of the other element, the two elements being separable from each other at the inward-facing surfaces of their transverse marginal and image portions so that a processing composition adapted to effect development of the latent image and recording of the visible image can pass between the transverse marginal and image portions. The

improved self-processing film unit of the present invention also comprises means for supplying the processing composition between the first transverse marginal portions to the image portions, the supplying means including a rupturable pod containing the processing composition and means for directing the composition from the pod, when ruptured, between the first transverse marginal portions to the image portions. The improved self-processing film unit of the present invention further comprises a leader underlying the two elements and the supplying means, the leader being removably coupled to the first and second longitudinal marginal portions of the lower element and permanently coupled to the supplying means. The improved self-processing film unit of the present invention further comprises means on the inward-facing surface of at least one of the second transverse marginal portions of the two elements for coupling the second transverse marginal portions to each other upon application of compressive force urging the second transverse marginal portions together. The improved self-processing film unit of the present invention further comprises a spacing member permanently coupled to the leader under and parallel with the second transverse marginal portions of the two elements to assist the compressive force in urging the second transverse marginal portions together. The improved self-processing film unit of the present invention may further comprise means adjacent to the second transverse marginal portions for receiving and retaining any excess portion of the processing composition from the image portions of the two elements. The receiving and retaining means may include an extension of the leader folded around and over the second transverse marginal portions, the end portion of the leader extension being removably coupled to the second transverse marginal portion of the upper element. The end portion may in turn be folded back upon itself to provide a back-folded portion and an overlying main portion, the back-folded portion being adjacent to the second transverse marginal portion of the upper element. The receiving and retaining means may further include means for sealing the receiving and retaining means closed upon application of compressive force after the excess processing composition has been received therein.

The invention, and its objects and advantages, will become more apparent in the detailed description of the illustrated embodiments presented below.

BRIEF DESCRIPTION OF THE DRAWINGS

In the detailed description of the illustrated embodiments of the invention presented below, reference is made to the accompanying drawings, in which:

FIG. 1 is a perspective view of a film unit in accordance with the preferred embodiment of the present invention, with portions thereof broken away for clarity of illustration;

FIG. 2 is an exploded view of the film unit of FIG. 1, showing its principal component parts;

FIG. 3 is an enlarged partial sectional view, taken along line 3—3 of FIG. 1, showing the trailing end portion of the film unit as it appears before the unit has passed between pressure-applying members;

FIG. 4 is an enlarged partial sectional view similar to FIG. 3 but showing the image portions of the photosensitive and process elements of the film unit disposed between a pair of juxtaposed pressure-applying members;

FIG. 5 is an enlarged sectional view taken along line 5-5 of FIG. 4, showing the image portions of the two elements disposed between the pressure-applying members;

FIG. 6 is an enlarged partial sectional view similar to FIG. 4 but showing the trailing end portions of the photosensitive and process elements of the film unit disposed between the pressure-applying members;

FIG. 7 is an enlarged partial sectional view, taken along line 7-7 of FIG. 6, showing the trailing end portions of the two elements disposed between the pressure-applying members;

FIG. 8 is an enlarged partial sectional view similar to FIG. 6 but showing the trap of the film unit disposed between the pressure-applying members;

FIG. 9 is an enlarged partial sectional view, taken along line 9-9 of FIG. 8, showing the trap of the film unit disposed between the pressure-applying members;

FIG. 10 is an enlarged partial sectional view similar to FIG. 8 but showing the film unit after it has been completely withdrawn from the pressure-applying members and after the photosensitive and process elements have been separated from the remainder of the unit;

FIG. 11 is an enlarged sectional view similar to FIG. 10 but showing only the two elements as they appear after reverting to their original configuration;

FIG. 12 is a perspective view of the elements of FIG. 11, with a corner of the process element turned up for clarity of illustration;

FIG. 13 is a partial top plan view of a film unit in accordance with the first alternative embodiment of the present invention, with portions thereof turned up for clarity of illustration;

FIG. 14 is an enlarged partial sectional view, taken along line 14-14 of FIG. 13, showing the trailing end portions of the photosensitive and process elements of the film unit disposed between a pair of juxtaposed pressure-applying members;

FIG. 15 is an enlarged sectional view, taken along line 15-15 of FIG. 14, showing the trailing end portions of the two elements disposed between the pressure-applying members;

FIG. 16 is a partial top plan view of a film unit in accordance with the second alternative embodiment of the present invention, with portions thereof turned up for clarity of illustration;

FIG. 17 is an enlarged partial sectional view, taken along line 17-17 of FIG. 16, showing the trailing end portions of the photosensitive and process elements of the film unit disposed between a pair of juxtaposed pressure-applying members; and

FIG. 18 is an enlarged sectional view, taken along line 18-18 of FIG. 17, showing the trailing end portions of the two elements disposed between the pressure-applying members.

DESCRIPTION OF THE ILLUSTRATED EMBODIMENTS

Because certain aspects of photographic film units and cooperating apparatus are well known, the following description is directed in particular to those elements forming, or cooperating directly with, the present invention, elements that are not specifically shown or described herein being understood to be selectable from those known in the art.

THE PREFERRED EMBODIMENT

FIGS. 1-12 of the drawings illustrate an improved self-processing film unit constructed in accordance with the preferred embodiment of the present invention.

Referring now to FIG. 1, a film unit 1 is shown comprising a carrier sheet or leader 2, an image-recording unit 3 including photosensitive and process elements 4 and 5, respectively, a supplying means 6 for supplying a fluid processing composition to the image-recording unit, and a trap 7 for receiving and retaining any excess portion of the processing composition from the image-recording unit.

15 The photosensitive and process elements 4 and 5 are accurately constructed to define sheets having straight edges, square corners, and appropriate borders, and are appropriately registered during manufacture to provide a uniformly flat, aesthetically pleasing structure that will maintain its integrity after processing. Except for the supplying means, trap, and carrying sheet or leader, image-recording unit 3 is supplied with all parts necessary for its processing in cooperation with photographic apparatus, and all such parts are permanently held together without adversely affecting the finished print.

Carrier sheet or leader 2 supports and is coupled to image-recording unit 3 and supplying means 6, and forms part of trap 7, the supplying means and trap being coupled to the recording unit in order to discharge the processing composition between the photosensitive and process elements at one end of the recording unit and to receive and retain any excess portion of the processing composition from between the two elements at the opposite end of the unit. Carrier sheet 2 is particularly adapted to facilitate handling of the entire film unit 1 from the first stages of its manufacture, through completion of the finished print, to disposal of all processing waste material. Carrier sheet 2 comprises an individual sheet that is shown directly coupled to only one image-recording unit, although it may also be coupled to other similar units in an assemblage of units. Carrier sheet 2 is adapted to facilitate its alignment with the other parts of the film unit during manufacture, transport of the film unit from an assemblage of such units during use in cooperating photographic apparatus, and its being rolled up with other processing waste material such as the supplying means and trap for disposal after processing.

50 Supplying means 6 and trap 7 are permanently coupled to carrier sheet 2, and are removably coupled to image-recording unit 3. The image-recording unit is removably coupled to the carrier sheet. As will be described more fully hereinafter, such an arrangement of permanent and removable couplings permits convenient removal of the image-recording unit (defining the finished print) from the carrier sheet, supplying means, and trap after processing. The carrier sheet, supplying means, and trap, which then comprise the processing waste material, can conveniently be rolled up and discarded, the carrier sheet surrounding the pod and trap to protect any sensitive environment (e.g., the user's clothing or skin) from any processing composition remaining in the waste material.

With regard to the image-recording unit 3, photosensitive element 4 thereof comprises a substantially flat, resilient support of transparent cellulose triacetate film

base defining a first or leading end 10, a second or trailing end 11, longitudinal edges 13 and 15, and a central or image portion 16. At least the image portion 16 supports one or more layers of image-receiving material, opaque reflecting material, and silver halide emulsion with associated dye and image-providing material. Such layers preferably are arranged in the foregoing order, the support being located near the bottom or lower face of the element adjacent to carrier sheet 2, so that the support protects that side of the unit, and the silver halide emulsion being located near the top or upper face of the element so that the emulsion is protected by the transparent process sheet 5. As will become more apparent hereinafter, the silver halide emulsion is adapted to be exposed through process sheet 5, i.e., from the top side of the unit, and the developed print is adapted to be viewed through the transparent support, i.e., from the bottom side of the unit.

Photosensitive element 4 further includes appropriate means, illustrated by imaginary lines as a border 20 comprising longitudinal border or marginal portions 20a, 20b and transverse border or marginal portions 20c, 20d, for defining an exposure frame within which a latent image can be developed and a print frame (preferably white) within which a visible image can be recorded. The exposure and print frames are coextensive and may be defined in any one of a number of ways including pre-flash and photoresist techniques applied to one or more layers of the element.

The process sheet or second element 5 also is preferably formed from a transparent material, such as cellulose triacetate film base, and defines a resilient, substantially flat sheet having leading and trailing ends, longitudinal edges, and a central or image portion corresponding to and coextensive with their counterparts in photosensitive element 4. To avoid excessive crowding of the drawing, separate reference numerals have not been applied to these corresponding parts of process sheet 5. It should be understood, however, that such parts are aligned with and can be referred to or located by the reference numerals applied to their counterparts in photosensitive element 4 just as they are referred to in the same or similar terms. In addition to facilitating the spreading of the processing composition, to be described more fully hereinafter, transparent process sheet 5 protects the top side of photosensitive element 4 while permitting exposure of the silver halide emulsion.

Photosensitive element 4 and process sheet 5 are rectangular and coextensive with each other, and are maintained in their preregistered, superposed, facing relationship by any permanent coupling means 21 to maintain the structural integrity of image-recording unit 3. As illustrated and described more fully in commonly assigned, copending U.S. Pat. application Ser. No. 70,836, entitled FILM UNIT and filed Sept. 9, 1970 in the name of Hubert Nerwin now abandoned, coupling means 21 may comprise a contact-sensitive, cohesive material applied to both photosensitive element 4 and process sheet 5. Other satisfactory coupling means may be provided by heat or sonic seals, or by adhesive material applied to either one or both of the photosensitive element and process sheet. Preferably, the coupling means extends along longitudinal marginal portions 20a and 20b, adjacent to longitudinal edges 13 and 15, respectively, from leading end 10 to trailing end 11. The resulting coupling should be suffi-

ciently impervious to the processing composition to prevent its premature escape from between the longitudinal edges during processing.

Regardless of the particular type of coupling means used, the photosensitive and process elements are secured substantially in direct contacting relationship, or the equivalent thereof, along their longitudinal marginal portions so that their central or image portions are retained in their preregistered, superposed relationship. As will be described hereinafter, transverse marginal portions 20c of elements 4 and 5 are resiliently separable to permit the introduction of processing composition between the two elements at their leading ends; similarly, transverse marginal portions 20d of elements 4 and 5 are resiliently separable to permit the discharging of any excess portion of the composition from between the two elements at their trailing ends.

Image-recording unit 3, comprising photosensitive element 4 and process sheet 5, is particularly adapted to cooperate with various parts of the more comprehensive film unit 1. Film unit 1 includes, in addition to image-recording unit 3, the carrier sheet or leader 2, supplying means 6, and trap 7, all of which cooperate with unit 3 to effect the recording of an image therein when used in suitable photographic apparatus.

Trap 7 generally comprises a pair of lifters 41 mounted on opposite ends of a spacing element 43 that is permanently coupled to the lower portion 45 of an extension 47 of carrier sheet 2, the upper portion 49 of the extension overlying lifters 41 and transverse marginal portion 20d of process sheet 5 to retain any received excess processing composition between the lifters.

Upper portion 49 of the carrier sheet extension terminates in an end portion or lip 51 that is folded back upon itself to provide a back-folded portion 53 and an overlying main portion 55, the back-folded portion being adjacent to, and removably coupled to, transverse marginal portion 20d of process sheet 5. The removable coupling comprises an adhesive coating 57 on back-folded portion 53 for separably coupling portion 53 to marginal portion 20d, coating 57 being applied to only small discrete areas of portion 53 to render the coupling easily separable or removable.

Use of a back-folded lip in this manner offers several advantages over a lip which is not so folded. First, removal of the lip of the trap from its position above transverse marginal portions 20d of image-recording unit 3 is rendered easier because the back-folded lip can simply be peeled or rolled back and thereby unfolded as removal takes place. Second, the thickness of back-folded portion 53 assists the compressive force in urging the transverse marginal portions 20d together, as will be explained in more detail hereinafter. Third, when the back-folded lip becomes unfolded upon its removal from image-recording unit 3, back-folded portion 53 provides an extension for the trap which safely covers the end of the flow of the excess processing composition into the trap, as will be described more fully with reference to FIGS. 8 and 10.

The lifters 41 are substantially incompressible and cooperate with carrier sheet extension 47 and spacing element 43 to define surfaces enclosing a chamber or void that is maintained even when that portion of the film unit passes between pressure-applying members of cooperating photographic apparatus.

Included in trap 7 is a means for sealing the trap closed upon application of compressive force urging the trap closed after any excess portion of the composition has been received therein. Such sealing means comprises a coating of adhesive or cohesive cement applied to one or more interior surfaces of the trap so that those surfaces will remain coupled to each other after the compressive force has been removed. As shown in FIG. 3, the lower and upper portions 45 and 49 of carrier sheet extension 47 have opposite interior surfaces 59 and 61 respectively. Permanently coupled to surface 59 is a spacing member 63 which serves a two-fold purpose that will be explained hereinafter. The leading end portion 65 of spacing element 43 overlaps the trailing end portion 67 of spacing member 63 as shown. Provided on the upward-facing surface of leading end portion 65 is a coating of moisture-sensitive cohesive cement 69. Similarly, there is provided on downward-facing surface 61 a coating of moisture-sensitive cohesive cement 71. As will be explained in more detail hereinafter, application of a compressive force F urging portions 65 and 49 together will bring the coatings of cohesive cement 69 and 71 into contact with each other and thereby cause trap 7 to remain sealed closed after the force F has been removed.

Supplying means 6 comprises cooperating parts which together define suitable means for supplying a processing composition to image-recording unit 3. Such parts include a rupturable container or pod 73 generally comprising a rectangular blank of vapor-impermeable material that is folded over upon itself to form a folded leading end 75, a first pair of longitudinal edges 77 which are permanently coupled together, a second pair of longitudinal edges 79 which are permanently coupled together, and a pair of trailing edges 81 which are rupturably coupled together so as to permit ready release of processing composition from the pod in response to hydraulic pressure generated by the composition when the pod is passed between pressure-applying members of cooperating photographic apparatus. The container or pod 73 cooperates with leading end 10 of image-recording unit 3 to discharge the processing composition between photosensitive element 4 and process sheet 5, and for this purpose is coupled to a directing means or funnel 83 having a trailing end portion inserted between the transverse marginal portions 20c of photosensitive element 4 and process sheet 5, as will be described more fully hereinafter.

Carrier sheet 2 comprises an elongate web of flexible material that can conveniently be cut as a single piece having the desired shape. The configuration illustrated permits assembly of each film unit independently of other such units and in a manner especially conducive to assembly-line or automated methods. By way of example only, the carrier sheet can be laid out on a flat vacuum table, and the various cooperating parts, such as spacing member 63, spacing element 43 with lifters 41 mounted thereon, image-recording unit 3, and supplying means 6, can then be appropriately coupled to the outstretched surface of the carrier sheet.

Carrier sheet 2 may also serve to interconnect various ones of a plurality of film units in an assemblage or pack thereof (not shown), and to transport the units in photographic apparatus such as a cartridge or camera (not shown). For that purpose, carrier sheet 2 is adapted to be folded in almost any desired manner at one or more locations along its leading end portion for

suitable attachment to other units. The assemblage may be assembled in many different arrangements, both simple and complex, with no significant change in the unit itself except, perhaps, in the manner of folding the carrier sheet or in the attachment of one or more supplemental leaders (not shown).

Carrier sheet 2 preferably is cut from a continuous roll of coated paper. Such paper should be flexible and easily folded while resisting tearing or cracking even after long periods of storage. Moreover, it should be strong in tension and have a protective coating to repel fluids, such as the processing composition, that might result in reducing its strength. The same coating can enhance the performance of the carrier sheet by reducing its coefficient of friction and thereby rendering it more slidable over other film units in an assemblage. The carrier sheet should have a slight resiliency, i.e., it should be neither so stiff nor so resilient as to interfere with its being folded to provide a compact and compressible stack of units. Also, the carrier sheet should accept a wide variety of coupling means, such as adhesives, cohesives, and seals (e.g., ultrasonic or heat), so that it can be suitably coupled to the various other parts comprising the overall film unit.

Carrier sheet 2 comprises a first or leading end portion 85, a second or trailing end portion 87, and a central or unit-supporting portion 89. The length of leading end portion 85 depends upon many factors, such as the manner in which a plurality of film units are to be connected in an assemblage thereof. In the illustrated embodiments, the carrier sheet of one film unit is adapted to be coupled to the carrier sheet of another film unit near the leading end of the other unit, and therefore extends somewhat beyond pod 73 as shown.

Should it be desired to couple the carrier sheet of one film unit to the carrier sheet of another film unit near the trailing end of the other unit, leading end portion 85 could be extended by an appropriate amount or a supplemental leader could be provided to increase the effective length of the carrier sheet.

The carrier sheet is provided with suitable coupling means, such as adhesives, cohesives, or seals 91, 93, 95, 97, and 99, for coupling pod 73, funnel 83, image-recording unit 3, spacer member 63, and spacer element 43, respectively, to the carrier sheet. The coupling means may be an adhesive applied only to the carrier sheet or only to the pod, funnel, image-recording unit, spacing member, and spacing element. Preferably, however, especially for the pod, funnel, spacing member, and spacing element, a cohesive is applied to the carrier sheet and to each of the parts to be coupled thereto, since a cohesive once applied, will adhere only to the same or a similar cohesive. Thus, a suitable cohesive may be applied to each of the parts at a plant location other than, and at a time prior to, their assembly. The parts, then, can be handled with the cohesive applied, and no particular precautionary measure need be taken to prevent them from sticking to the handling apparatus. When the parts are assembled in their intended contacting relationship, however, the cohesive on each contacting part immediately becomes effective to couple those parts together in the desired manner, e.g., removably in the case of the image-recording unit or permanently in the case of the pod, funnel, spacing member, and spacing element.

The coupling means may be applied to the entire contacting area of each part or to only a portion of such

area. Preferably, the cohesive is applied to a substantial portion of each contacting area of the pod, funnel, spacing member, and spacing element to provide a permanent coupling between those parts and the carrier sheet, but is applied to only small discrete portions of each contacting area of the image-recording unit to provide a separable or removable coupling between that part and the carrier sheet. Also, corner portions 101 of image-recording unit 3 may be left free to separate from the carrier sheet when grasped by the user to facilitate removal of image-recording unit 3 from the remainder of film unit 1 after processing.

Funnel 83 and trap 7 are also removably coupled to image-recording unit 3. Such coupling, however, may be only functional. As will be described more fully hereinafter, the lips at the trailing end of funnel 83 are disposed between the transverse marginal portions 20c of photosensitive and process elements 4 and 5, and transverse marginal portions 20d of the photosensitive and process elements are disposed under end portion 51 of upper portion 49 of carrier sheet extension 47, no adhesive, cohesive, or other coupling means being required, although in this embodiment the adhesive coating 57 is provided on back-folded portion 53, as already described, to removably couple portions 53 and 20d to each other.

Referring now to FIG. 4, film unit 1 is intended to be used in photographic apparatus such as a camera having stepped pressure-applying members 103 and 105 that are urged toward each other by a spring or other biasing means 104, as illustrated and described in commonly assigned, copending U.S. Pat. application Ser. No. 70,836, entitled FILM UNIT and filed Sept. 9, 1970 in the name of Hubert Nerwin now abandoned. In operation, raised shoulder portions 103a and 105a of pressure-applying members 103 and 105 are adapted to ride on longitudinal marginal portions 20a and 20b of image-recording unit 3 as the unit is pulled between the two members, while recessed central portions 103b and 105b of members 103 and 105 are adapted to rupture pod 73 and spread its processing composition C in a uniform layer between photosensitive and process elements 4 and 5.

As the processing composition is expelled from pod 73 and distributed between the photosensitive and process elements, hydraulic forces within the composition separate the two elements throughout their central or image portions 16 and force them (with the carrier sheet) into engagement with the recessed central portions 103b and 105b of the pressure-applying members. The distance between central portions 103b and 105b is selected to spread the composition in a layer of suitable initial thickness, e.g., 0.003 inches. Since the total thickness of photosensitive element 4, process sheet 5, and carrier sheet 2 is automatically accounted for by the engagement of their longitudinal marginal portions with raised shoulder portions 103a and 105a of the pressure-applying members, it has been found that the desired initial thickness can be had by providing each of the members with a recessed central portion approximately equal in height to three-fourths of such thickness.

As the processing composition is distributed, it immediately begins to permeate the various layers of the photosensitive element to initiate processing. Additionally, various components of the processing composition, including water, begin to escape or dissipate en-

tirely through or otherwise from between the photosensitive and process elements to the surrounding atmosphere, resulting eventually in the evaporation of most of the processing composition. The composition comprises only a very small percentage of solids, e.g., less than 5 percent, and most of the remainder of the composition (essentially water) eventually escapes from between the two elements within a few hours. As a result, the hydraulic forces holding the photosensitive and process elements apart are relieved, and the resiliency of the elements effects their return to facing engagement. By this time, the image-recording unit again has assumed its original uniformly flat configuration. Since the image-recording unit 3 is adapted to be stripped from the carrier sheet, as described more fully herein-after, the finished print will be presented in the very same complete structure that was accurately cut and assembled as the image-recording unit at the time of manufacture.

Certain additional features of a film unit according to the preferred embodiment of the present invention will now be described. Referring to FIG. 2, the processing composition directing means or funnel 83 is shown as comprising a pair of superposed sheets 107 and 109 of flexible, vapor-impervious material, each sheet having longitudinal edge portions 111 and 113 along which the two sheets are permanently coupled to each other, and transverse edge portions 115 and 117 forming, respectively, the leading and trailing end portions of the funnel. Trailing edges 81 of pod 73 are inserted between and permanently coupled to transverse edge portions 115 of funnel 83, as shown, to enable funnel 83 to receive processing composition from pod 73 when the pod is ruptured. At the trailing end of funnel 83, edge portions 117 are inserted between but not otherwise coupled to transverse marginal portions 20c of the photosensitive and process elements 4 and 5. The leading portion of the inward-facing surface of each transverse marginal portion 20c is provided with a cohesive coupling means 119 which is covered over by the adjacent one of the edge portions 117 of funnel 83. The cohesive coupling means 119 on each portion 20c comprises a coating of cohesive cement which does not adhere readily to the adjacent edge portion 117 but which will cohere readily with the like coating of cohesive cement on the opposite portion 20c after edge portions 117 have been withdrawn from between the two portions 20c. Thus, after edge portions 117 have been withdrawn, the portions 20c need merely be pressed together by the user in order to effect the desired coupling. Sheets 107 and 109 of funnel 83 are separable from each other between their longitudinal edge portions 111 and 113 so that the processing composition can pass from the pod between the two sheets to the image-recording unit.

As shown in FIGS. 3, 4, and 6, the transverse marginal portions 20d of image-recording unit 3 are defined by a photoresist coating 121 applied to the interior or inward-facing surface of photosensitive element 4. To provide for the coupling of elements 4 and 5 to each other along their transverse marginal portions 20d after the excess processing composition has passed therebetween to trap 7, a coupling means is applied to the interior or inward-facing surface of at least one of the transverse marginal portions 20d, the coupling means being adapted to couple portions 20d to each other upon application of a compressive force urging

those portions together. Such compressive force is applied by pressure-applying members 103 and 105 as the film unit is drawn between them. The trailing portion of the inward-facing surface of each transverse marginal portion 20d is provided with a moisture-sensitive, or moisture-activated cohesive coupling means 123, although a suitable adhesive could be applied to only one of those surfaces in order to effect the desired coupling. The moisture-sensitive cohesive coupling means 123 on each portion 20d comprises a coating of cement which becomes activated to cohere readily with the like coating of cement on the opposite portion 20d only after at least one of those coatings has been moistened by the excess processing composition. Thus, after the excess processing composition has passed therebetween, the portions 20d need merely be urged together by the pressure-applying members in order to effect the desired coupling.

FIG. 4 shows film unit 1 as the pressure-applying members 103 and 105 are positioned above and below, respectively, the image portions 16 of elements 4 and 5, and as the processing composition C is passing between coatings 123. FIG. 5 shows how the raised shoulder portions 103a and 105a of the pressure-applying members engage the longitudinal marginal portions 20a and 20b, also defined by photo-resist coating 121, of elements 4 and 5, and how the recessed central portions 103b and 105b of the pressure-applying members permit the image portions 16 of elements 4 and 5 to become separated by the processing composition to the extent of the thickness of the composition desired for processing.

FIG. 6 shows film unit 1 as the pressure-applying members 103 and 105 are positioned above and below, respectively, the transverse marginal portions 20d of elements 4 and 5, member 103 being shown on top of lip 51 of trap 7. It will be seen in FIG. 7 that back-folded portion 53 of lip 51 and spacing member 63 on carrier sheet 2 are slightly narrower in width than the recessed central portions 103b and 105b of the pressure-applying members. This is to permit the thicknesses of portion 53 and member 63 to compensate for the depths of the recessed central portions 103b and 105b relative to the raised shoulder portions 103a and 105a, to thereby permit the pressure-applying members 103 and 105 to press the transverse marginal portions 20d firmly together to effect the desired coupling of portions 20d by means of the cement coatings 123.

FIG. 8 shows film unit 1 as the pressure-applying members 103 and 105 are positioned above and below, respectively, the leading end portion of the trap 7. It will be seen that upper portion 49 of carrier sheet extension 47 has been urged downward by pressure-applying member 103, and at the same time lower portion 45 has been urged slightly upward, until the moisture-sensitive cohesive cement coatings 71 and 69 have been brought into contact with each other to seal trap 7 closed. It will be seen also that, as upper portion 49 is urged downward, lip 51 is caused to unfold and thereby become separated from image-recording unit 3. As shown in FIG. 9, the leading end portion 65 of spacing element 43 and spacing member 63 are slightly narrower in width than the recessed central portions 103b and 105b of the pressure-applying members. This is to permit the thicknesses of portion 65 and member 63 to compensate for the depths of the recessed central portions 103b and 105b relative to the raised shoulder

portions 103a and 105a, to thereby permit the pressure-applying members 103 and 105 to press portions 49 and 65 firmly together to effect the desired coupling of those portions by means of cement coatings 71 and 69.

FIG. 10 shows trap 7 after it has been sealed closed with the unfolded lip 51 extending forward over spacing member 63, and image-recording unit 3 separated from the carrier sheet with the processing composition 10 C still confined between elements 4 and 5. FIG. 11 shows unit 3 after the processing composition has been absorbed by or evaporated through or between elements 4 and 5, the two elements having returned to their initial positions wherein their image portions are in facing contact with each other. FIG. 12 is a perspective view of unit 3 with a corner of element 5 turned up to better illustrate its component parts.

The most convenient manner of removing image-recording unit 3 from supplying means 6, after all of film unit 1 has passed between the pressure-applying members, is to first flex or bend carrier sheet 2 downwardly at its trailing end 87, thereby causing lip 51 to be pulled completely away from transverse marginal portions 20d and the carrier sheet to be stripped from image-recording unit 3. Preferably, the image-recording unit is significantly less flexible than the carrier sheet, and therefore tends to remain relatively flat. The next step is to pull the leading end 85 of the carrier sheet, and with it the pod and funnel, away from the image-recording unit. This causes the trailing end portion of the funnel to become completely withdrawn from the leading end portion of image-recording unit 3. The user can then press the leading portions of the transverse marginal portions 20c together so that the cohesive coupling means 119 will effect the desired coupling at that point.

Should bending of the carrier sheet in the above-described manner prove ineffective as a means of separating the image-recording unit from the supplying means, trap, and carrier sheet, the user can insert a fingernail or other object between the image-recording unit and the carrier sheet at the unattached corner 101 so as to grasp the unit and more forcefully separate it from the other parts in a manner similar to that described above.

The pod, funnel, and trap remain with the carrier sheet after the image-recording unit has been removed therefrom, and can be rolled up in the carrier sheet to enclose any remaining processing composition and thereby protect the immediate environment, e.g., the user's clothing or skin, from the composition.

THE FIRST ALTERNATIVE EMBODIMENT

FIGS. 13-15 illustrate an improved self-processing film unit constructed in accordance with the first alternative embodiment of the present invention. Parts that are the same in both the preferred embodiment and the first alternative embodiment are designated by the same reference numerals, whereas parts that differ are designated by the same reference numerals primed. As will be seen, the first alternative embodiment is the same as the preferred embodiment except that in the first alternative embodiment, the upper portion 49' of the carrier sheet extension 47' terminates in an end portion or lip 51' that is not folded back upon itself to provide a back-folded portion and an overlying main portion as in the preferred embodiment. Instead, lip 51'

provides only a single thickness of carrier sheet material overlying and removably coupled to the transverse marginal portion 20d of process sheet 5 by means of adhesive coating 57 as shown in FIG. 14. As can be seen in FIGS. 13 and 15, lip 51' and spacing member 63 are slightly narrower in width than the recessed central portions 103b and 105b of the pressure-applying members to permit the thicknesses of lip 51' and member 63 to compensate for the depths of the recessed central portions 103b and 105b, to thereby permit the pressure-applying members to press the transverse marginal portions 20d firmly together to effect the desired coupling of portions 20d by means of the cement coatings 123. In all other respects, the two embodiments are identical.

THE SECOND ALTERNATIVE EMBODIMENT

An improved self-processing film unit constructed in accordance with the second alternative embodiment of the present invention is illustrated in FIGS. 16-18. 20 Parts in this embodiment that are identical to those in the preferred embodiment are designated by like reference numerals, whereas differing parts are designated by the same numerals double-primed. In this embodiment, the carrier sheet 2" at its trailing end terminates flush with the trailing end 11 of photosensitive element 4, and the carrier sheet extension 47" comprises a separate sheet of carrier sheet material whose leading end portion 125 underlies and is permanently coupled to the trailing end of the carrier sheet, as shown in FIG. 25 17, by means of adhesive cement 127. End portion 125 and end portion or lip 51" are both slightly narrower in width than the recessed central portions 103b and 105b of the pressure-applying members to permit the thicknesses of those portions to compensate for the 30 depths of the recessed central portions 103b and 105b, to thereby permit the pressure-applying members to press the transverse marginal portions 20d firmly together to effect the desired coupling of portions 20d by means of the cement coatings 123. As shown in FIG. 35 16, upper portion 49" of carrier sheet extension 47" is of such narrower width nearly as far back as the leading edges of lifters 41, so that the thicknesses of both that portion and the equally narrow leading end portion 65 of spacing element 43 can similarly compensate for the depths of recessed central portions 103b and 105b to thereby permit the pressure-applying members to press portions 49" and 65 firmly together to seal the trap closed by means of the cement coatings 71 and 69. It will thus be seen that a separate spacing member such as the member 63 used in the preferred and first alternative embodiments is not necessary in this embodiment, and is therefore eliminated.

The invention has been described in detail with particular reference to the illustrated preferred and alternative embodiments thereof, but it will be understood that variations and modifications can be effected within the spirit and scope of the invention.

I claim:

1. In a self-processing film unit comprising a pair of preregistered, superposed elements including a layer of photosensitive material for establishing a developable latent image of a subject to which said photosensitive material can be exposed and a layer of image-recording material for recording a visible image in response to development of the latent image, each of said elements having first and second longitudinal marginal portions

along which said elements are permanently coupled to each other, first and second transverse marginal portions interconnecting said longitudinal marginal portions, and an image portion intermediate said marginal portions, each portion of each element having an inward-facing surface, each inward-facing surface of one element facing a corresponding inward-facing surface of the other element, said elements being separable from each other at the inward-facing surfaces of their transverse marginal and image portions so that a processing composition adapted to effect development of the latent image and recording of the visible image can pass between said transverse marginal and image portions;

- 15 means for supplying said processing composition between said first transverse marginal portions to said image portions, said supplying means including a rupturable pod containing said processing composition and means for directing said composition from said pod, when ruptured, between said first transverse marginal portions to said image portions; the improvement comprising:
a leader underlying said elements and said supplying means, said leader being removably coupled to said first and second longitudinal marginal portions of one of said elements and permanently coupled to said supplying means;
means on the inward-facing surface of at least one of said second transverse marginal portions for coupling said second transverse marginal portions to each other upon application of compressive force urging said second transverse marginal portions together after supplying said processing composition;

30 a spacing member permanently coupled to said leader in alignment with said second transverse marginal portions of said elements to assist the compressive force in urging said second transverse marginal portions together.

2. The self-processing film unit claimed in claim 1

wherein said coupling means includes moisture-sensitive means for coupling said second transverse marginal portions to each other after a portion of said composition has passed therebetween.

45 3. The self-processing film unit claimed in claim 1 further comprising means adjacent to said second transverse marginal portions for receiving and retaining any excess portion of said composition from said image portions.

50 4. The self-processing film unit claimed in claim 3 wherein said receiving and retaining means includes means for sealing said receiving and retaining means closed upon application of compressive force urging said receiving and retaining means closed after the excess portion of said composition has been received therein.

55 5. The self-processing film unit claimed in claim 3 wherein said receiving and retaining means includes an extension of said leader folded around and over said second transverse marginal portions.

60 6. The self-processing film unit claimed in claim 5 wherein said leader extension includes an end portion removably coupled to the second transverse marginal portion of the upper one of said elements.

65 7. The self-processing film unit claimed in claim 5 wherein said leader extension includes an end portion folded back upon itself to provide a back-folded por-

tion and an overlying main portion, said back-folded portion being adjacent to the second transverse marginal portion of the other of said elements and forming said spacing member.

8. The self-processing film unit claimed in claim 7 wherein said back-folded portion is removably coupled to said second transverse marginal portion of the other of said elements.

9. The self-processing film unit claimed in claim 5 wherein said leader extension includes lower and upper portions extending beyond said elements, said lower and upper portions having opposing interior surfaces, and wherein said receiving and retaining means further includes means disposed between said interior surfaces for maintaining said surfaces in spaced relationship in opposition to the influence of compressive force urging said lower and upper portions together.

10. The self-processing film unit claimed in claim 9 wherein said receiving and retaining means further includes means on one of said interior surfaces for coupling said one interior surface and said maintaining means to each other upon application of the compressive force urging said lower and upper portions together.

11. The self-processing film unit claimed in claim 10 wherein said one surface is the interior surface of said upper portion of said leader extension, and wherein said coupling means on said one surface includes moisture-sensitive means for coupling said surface and said maintaining means to each other after the excess portion of said composition has passed therebetween.

12. The self-processing film unit claimed in claim 9 wherein said receiving and retaining means further includes means on said maintaining means for coupling one of said interior surfaces and said maintaining means to each other upon application of the compressive force urging said lower and upper portions together.

13. The self-processing film unit claimed in claim 12 wherein said one surface is the interior surface of said upper portion of said leader extension, and wherein said coupling means on said maintaining means includes moisture-sensitive means for coupling said surface and said maintaining means to each other after the excess portion of said composition has passed therebetween.

14. In a film unit processable by a processing composition, said film unit comprising a first element and a second element in superposed relationship, said elements including a layer of photosensitive material for establishing a developable latent image and a layer of image-recording material for recording a visible image, each of said elements having a pair of lateral border portions along which said elements are coupled to each other, a transverse border portion interconnecting said lateral border portions, and an image portion intermediate said lateral border portions, each portion of each element having an inward-facing surface, each inward-facing surface of one element facing a corresponding inward-facing surface of the other element, said elements being separable from each other at the inward-facing surfaces of their image portions to permit a distribution of the processing composition therebetween; the improvement comprising:

means on the inward-facing surface of the transverse border portion of at least one of said elements for coupling said elements to each other at said trans-

verse border portion upon application of a compressive force urging said transverse border portions together after distribution of said processing composition;

a carrier member separably coupled to said first element, said carrier member being removable from said first element after the distribution of the processing composition between said image portions; and

spacing means coupled to said carrier member and in alignment with said transverse border portion for assisting the compressive force urging said transverse border portions together, said spacing means being removable together with said carrier member from said first element.

15. The film unit claimed in claim 14 wherein said coupling means includes moisture-activated coupling means.

16. The film unit claimed in claim 14 further comprising means for supplying the processing composition to said image portions.

17. The film unit claimed in claim 14 further comprising means adjacent to said transverse border portions for receiving and retaining any excess portion of the processing composition from said image portions.

18. The film unit claimed in claim 17 wherein said receiving and retaining means includes means for sealing said receiving and retaining means closed upon application of a compressive force urging said receiving and retaining means closed after the excess portion of the processing composition has been received therein.

19. The film unit claimed in claim 17 wherein said receiving and retaining means includes a portion of said carrier member extending around said transverse border portions.

20. The film unit claimed in claim 19 wherein said carrier portion is in separable overlapping contact with the transverse border portion of said second element.

21. The film unit claimed in claim 19 wherein said carrier portion is folded back upon itself to provide a back-folded portion and an adjacent main portion, said back-folded portion being separably coupled to the transverse border portion of said second element and forming said spacing means.

22. The film unit claimed in claim 19 wherein said carrier portion includes first and second portions extending beyond said elements, said first and second portions having opposing interior surfaces, and wherein said receiving and retaining means further includes means disposed between said interior surfaces for maintaining said surfaces in spaced relationship in opposition to influence of a compressive force urging said first and second portions together.

23. The film unit claimed in claim 22 wherein said maintaining means is coupled to the interior surface of said first portion, and wherein said receiving and retaining means further includes means for coupling the interior surface of said second portion to said maintaining means upon application of the compressive force urging said first and second portions together.

24. The film unit claimed in claim 23 wherein said means for coupling the interior surface of said second portion to said maintaining means includes moisture-activated coupling means.

25. In a film unit for establishing a latent image of a subject to which said film unit is adapted to be exposed and for recording a visible image in response to distri-

bution of a processing composition across the latent image, said film unit comprising a pair of superposed elements including photosensitive material for establishing the latent image and image-recording material for recording the visible image, each of said elements having first and second marginal portions and an image portion intermediate said marginal portions, each portion of each element having an inward-facing surface, each inward-facing surface of one element facing a corresponding inward-facing surface of the other element, said elements being adapted to receive the processing composition between the inward-facing surfaces of their image portions; the improvement comprising:
 coupling means, on the inward-facing surface of at least one of said second marginal portions, for maintaining said second marginal portions in contact with each other upon application of a compressive force urging said second marginal portions together after distribution of said processing composition;
 trapping means, removably disposed in contact with said second marginal portions and having opposing interior surfaces, for receiving and retaining any excess portion of the processing composition from between said image portions; and
 sealing means, on at least one of said interior sur-

- faces, for maintaining said trapping means in a closed condition upon application of a compressive force urging said trapping means closed after distribution of said processing composition.
- 5 26. The film unit claimed in claim 25 wherein said coupling means includes moisture-activated coupling means.
- 10 27. The film unit claimed in claim 25 wherein said sealing means includes moisture-activated sealing means.
- 15 28. The film unit claimed in claim 25 further comprising supplying means, removably disposed in contact with said first marginal portions, for providing the processing composition in between said image portions.
- 20 29. The film unit claimed in claim 28 further comprising a carrier member removably coupled to said elements and permanently coupled to said trapping means and said supplying means.
- 25 30. The film unit claimed in claim 29 further comprising spacing means, permanently coupled to said carrier member substantially in alignment with said coupling means and said sealing means, for assisting the compressive forces urging said second marginal portions together and said trap means closed.
